XEROGRAPHIC POWDER-IMAGE TRANSFER SQUEEGEE

Frederick W. Hudson, West Henrietta, N. Y., assignor to The Haloid Company, Rochester, N. Y., a corporation of New York

Application January 21, 1954, Serial No. 405,392

1 Claim. (Cl. 118—500)

This invention relates to a xerographic powder-image transfer squeegee and has for its purpose to afford an implement by which an operator can effectively hold a transfer sheet in uniform and proper contact with a powder-image on an xerographic plate while the powder-image is being transferred from the plate to the transfer sheet.

A powder-image is usually transferred from a xerographic plate to a transfer sheet by imposing an electrostatic charge on the transfer sheet and if good contact is not maintained between the xerographic plate and transfer sheet during the charging operation, incomplete transfer and a poor copy may result. Such incomplete transfer will occur with paper transfer sheets and is particularly true where the powder-image is transferred to a "Multi-lith" mat, due to high humidity conditions and when a change in humidity causes the mat to curl or buckle, and it is a particular purpose of the invention to insure proper uniform contact between the xerographic plate and mat at the point or area where the electrostatic charge is applied to effect transfer of the image.

The invention is especially applicable to xerographic copiers of the general type in which a mat or transfer sheet positioned on a powder-image and xerographic plate are moved into a developer chamber under a charging unit that extends across the transfer sheet, and it is a further purpose of the invention to afford an implement that can be easily manipulated by the operator and is effective to hold a transfer sheet in uniformly close contact with the xerographic plate during transfer and at the line where the electrostatic charge is imposed, so that as the xerographic plate and transfer sheet are moved into the cabinet beneath the charging unit, they are always held in proper contact at the exact point or along the exact line of transfer rather than in advance of or behind such line, thus resulting in effective and complete transfer of the powder-image from the xerographic plate onto the transfer sheet.

Another object of the invention is to afford an implement which when held in operative position automatically engages the switch controlling the electrostatic charging unit and at the same time positions the implement with relation to the front wall of the development cabinet, while the sheet-engaging portion of the implement extends into the cabinet and contacts the transfer sheet along the line of transfer where the charge is imposed on the transfer sheet.

An additional purpose is to provide a simple device that can be easily manipulated, which is economical to manufacture, and can be produced from sheet plastic which insures proper flexibility of the sheet-engaging portion so as to afford sufficient pressure without excessive pressure.

To these and other ends, the invention consists in the construction and arrangement of parts that will appear clearly from the following description when read in conjunction with the accompanying drawings, the novel fea-

2

tures being pointed out in the claim following the specification.

In the drawings:

Fig. 1 is a perspective view showing one practical embodiment of the invention;

Fig. 2 is a perspective view showing the implement in operative position in relation to a transfer sheet and xerographic plate, immediately prior to inserting them into the development chamber of a copier apparatus, and

Fig. 3 is a vertical sectional view taken centrally through the parts shown in Fig. 2, illustrating the position when the transfer sheet and xerographic plate have been partially inserted into the development chamber.

Referring more particularly to the drawings, which are intended merely as illustrative of one practical form of the device, 1 designates a body portion preferably of stiff plastic material and of generally rectangular form having a length corresponding to the width of the transfer sheet and xerographic plate, while 2 designates a forwardly projecting sheet-engaging portion with a straight front edge and preferably of plastic material, somewhat thinner and more flexible than the body portion 1, so that when its front straight edge is engaged with the transfer sheet and proper pressure applied by the operator to the body portion 1, the front edge of the sheet-engaging portion 2 acts to press the transfer sheet lightly and evenly against the xerographic plate and the powder-image thereon.

The flexible sheet-engaging portion 2, in the structure shown, overlaps and is suitably attached to the front area of the body portion 1 by suitable adhesive or otherwise, although it will be understood that the plastic portions 1 and 2 may be integrally or otherwise formed and the entire structure may be constructed of materials other than plastic.

In using the implement, the operator inserts and holds it in approximately the position shown in Fig. 3 in which the front edge of the transfer sheet-engaging portion 2 is located against the transfer sheet 3 and beneath the electrostatic charging unit 4, the front edge of the sheet-engaging portion 2 extending along a line across the transfer sheet where transfer takes place at any given instant as the parts are moved along under the charging unit, and in proximity to the area on which the electrostatic charge is imposed at any given instant.

It is desirable to position the paper-engaging edge of the squeegee automatically and accurately in relation to the charging unit and to operate the switch which controls the charging unit by the insertion of the squeegee, and these functions are accomplished in the following manner.

5 designates the push-button switch located on the front wall 6 of the development cabinet of the copier and in order to effect operation of switch 5, there is provided an upstanding plate or flange 7 preferably of the general form illustrated in Fig. 1 and having its lower edge cemented or otherwise fixedly attached to the body portion 1 while flange 7 extends forwardly from the body portion 1 above the sheet-engaging portion 2 and spaced therefrom, terminating in a vertical edge to which is attached the right-angled plate 8 or stop which engages switch 5 and closes the electrostatic unit circuit when the squeegee is inserted into operative position, as shown in Fig. 2.

Thus the plate or stop 8 limits the inward movement of the sheet-engaging portion 2 at one end while the position of the opposite end of the sheet-engaging portion 2 is determined by a plate or flange 9, the lower edge of which is fixedly attached to the body portion 1, the flange 9 extending thence forwardly above and in spaced relation to the sheet-engaging portion 2 while the front edge of wall 9, as indicated at 10, constitutes a vertical

surface or stop which engages the front wall 6 of the copier cabinet, and together with the aforementioned stop 8 limits inward movement of the sheet-engaging portion 2 as the device is inserted into the cabinet with the straight front edge of portion 2 engaged with the transfer sheet, as shown in Fig. 3.

In order to enable the operator readily to grasp the implement and hold it in operative position, there is provided a finger-piece 11 rigidly attached to the underside of the body portion 1 in proximity to its rear edge and extending downwardly therefrom, preferably in the form of a plastic lug which is adhesively secured to the body portion 1. Thus when the device is resting on a surface, the finger-piece 11 elevates the rear edge of the body portion, enabling the operator to grasp the same easily and by holding the rear edge and finger-piece 11, the device can readily be inserted in the position shown in Fig. 2 with the front edge of the portion 2 in contact with the transfer sheet along the line where transfer takes place.

The operator inserts the squeegee to the position illustrated in Fig. 2, operating the switch 5 which closes the circuit to the electrostatic charging unit 4, and by holding the body portion 1 firmly and pressing it toward the copier cabinet and at the same time imposing a slight downward pressure, the transfer sheet-engaging portion 2 is flexed slightly and its forward edge held in close and uniform contact with the transfer sheet while the xerographic plate and transfer sheet are moved into the cabinet.

While the invention has been described with reference to the particular construction shown herein, it is not confined to the details illustrated, and this application is intended to cover such modifications or departures as may come within the purposes of the improvement or the scope of the following claim.

I claim:

A powder-image transfer squeegee for use in combination with a xerographic copier including a copier cabinet

having a slot in its front surface into which a plate carrying a powder image and a transfer sheet may be inserted and removed and having a depressable button on its outer front surface to operate means to cause transfer of a powder image from a plate member inserted in the slot to transfer material on the powder image, said improved squeegee comprising a stiff flexible plastic body portion, a stiff flexible plastic sheet-engaging portion overlapping and attached to said body portion, said sheet-engaging portion extending a substantial distance forwardly of the body portion and being somewhat thinner and more flexible than the body portion the rear edge of the sheet-engaging portion being permanently attached to the forward edge of the body portion, a stop of plastic material rigidly attached at the front edge of said body portion and extending over said sheet-engaging portion and engageable at its front end with the front wall of a xerographic developing cabinet, a second stop of plastic material having its bottom edge rigidly attached to the front edge of said body portion and located above and extending over said sheet-engaging portion, a right-angled plastic plate rigidly attached to the forward edge of said last mentioned stop and engageable with the depressable button on the front surface of the copier cabinet, and a finger-piece rigidly secured to the underside of said body portion in proximity to its rear edge.
